Primary Examiner — Ryan Harvey(74) *Attorney, Agent, or Firm* — Collard & Roe, P.C.(57) **CLAIM**

The ornamental design for an exercise platform, as shown and described.

DESCRIPTION

FIG. 1 is a front view of an exercise platform; FIG. 2 is a first end view of the exercise platform of FIG. 1; FIG. 3 is a second end view of the exercise platform of FIG. 1 opposite the view of FIG. 2;

FIG. 4 is a left-side view of the platform based upon the orientation of FIG. 1;

FIG. 5 is a right-side view of the exercise platform based upon the orientation of FIG. 1;

FIG. 6 is a back view of the exercise platform opposite the top side view of FIG. 1 with recesses for receiving a support bracket at the top end;

FIG. 7 is a front-left perspective view of the exercise platform thereof;

FIG. 8 is a front-right perspective view of the exercise platform thereof; and,

FIG. 9 is a side view of the exercise platform elevated on one side with a support bracket.

The broken lines and areas within the broken lines illustrate portions of the exercise platform that form no part of the claimed design.

1 Claim, 7 Drawing Sheets(56)
